2 Claims. (Cl. 182—189)

This invention relates to staircase structures and provides improved prefabricated elements for a staircase.

A staircase serving to interconnect floors situated at different levels of a building is disposed in a so-called well. The continuous portion of a staircase between adjacent floors is called a flight, and usually comprises a pair of parallel, opposed, sloping beams called stringers supporting the steps of the staircase. Conventional staircases have been made in different forms and from a variety of materials including stone, wood, steel, and concrete. However, even to the present day, the erection of staircases is usually performed by time-honoured techniques involving extensive use of scaffolding and considerable labour, even when certain of the component elements, such as stringers and steps, have been prefabricated in the workshop.

This invention sets out to overcome these difficulties and to provide component elements for a staircase which will be rigid and strong yet relatively lightweight, capable of being manufactured in large quantities by mass production methods, and of being rapidly and easily erected on site without scaffolding.

The invention provides a staircase comprising in combination at least one prefabricated stringer member and a plurality of prefabricated step members adapted for attachment across the stringer member in longitudinally spaced relation along it, the stringer and each step member being provided with cooperating guide surfaces interengageable for positioning and centering each step member in proper relation with the stringer member transversely of the latter, and being further provided with cooperating latching means interengageable for latching each step member in proper relation with the stringer member longitudinally of the latter.

A feature of the invention relates to a stringer member adapted to be quickly and easily mounted between the adjacent floors of a building. In accordance with this feature of the invention the ends of the improved stringer are conformed for seating engagement in a pair of respective, lower and upper, cradle members having cooperating means for retaining the related ends of the stringer. Desirably, provision is made for interposing vibration-preventing means between the ends of the stringer and the cradles.

Yet other features of the invention will stand out from the ensuing description and the accompanying drawings, which relate to an exemplary embodiment of the invention.

FIG. 1 is a perspective view of a staircase according to the invention during erection in a building;

FIG. 2 is a perspective view showing a stringer about to be engaged at its upper and lower ends into supporting cradle members projecting from columns of the stairway;

FIG. 3 illustrates the upper part of a staircase in vertical section;

FIG. 4 is a vertical cross section of the stringer shown in FIG. 3;

FIG. 5 shows a blank prior to its being formed into a step;

FIG. 6 shows the blank of FIG. 5 partly shaped into a step.

The building framework partly shown in FIG. 1 includes columns 1 supporting beams 2 and 3, at two dif-

2

ferent floor levels. Supported on the beams 2 and 3 at each level are floor structures 4 and 4a. There is further shown an intermediate floor 5 positioned at a level halfway between floors 4 and 4a, and laterally offset therefrom. Between the floors 4 and 5 there extends a single, sloping stringer 6 centrally of a flight of stairs, and supporting a series of steps 7 across it. The floors 5 and 4a are similarly interconnected by a stringer and steps, to provide an upper flight of stairs in reverse relation to the lower flight interconnecting the floors 4 and 5.

As shown in FIG. 2, a column 1a comprises a vertically disposed flanged channel section, having a cradle member 8a welded to a side of it so as to project horizontally from the column. The cradle member 8a comprises a V-shaped channel section 9 having horizontal side flanges 10, and a shallower flanged channel 11 fitted into the V-channel to provide a sort of triangular box-beam, as clearly shown in FIG. 4, with the flanges of the shallow channel 11 being fitted over and welded to the flanges 10 of the V-channel. One end of this cradle member has a reinforcing plate 12 welded across it, which in turn is welded to the flanges of the column 1a. The other free end of the cradle member is scarfed at a downward angle so that the bottom of the V-channel juts outward, as is visible in FIG. 2. The sidewalls of the channels 9 and 11 are formed with registering holes 13 serving to secure the stringer within the cradle as will be later explained.

In the lower part of FIG. 2, there is shown from the rear a further column 1b similar to column 1a, and a cradle member 8b projecting from it and similar to the cradle 8a just described.

FIG. 2 shows a stringer member in position for being engaged at its ends into the two cradle members 8a and 8b for support therein. The stringer is seen to include two horizontal end sections a and b, and a sloping intermediate section c. The three sections are scarfed and welded to one another at their corresponding ends. It will be noted that the upper and lower horizontal end sections a and b are not necessarily of equal length, and one or both of them may be made long enough to constitute in effect a landing joist.

Each of the three sections of the stringer has substantially the same cross sectional contour as that of the cradle 8. That is, each said section comprises a V-channel 9 having horizontal outer flanges and having a shallow channel 11a fitted in it. However, certain differences present between the channels 11 and 11a of the cradle members and stringer respectively will be noted later with reference to FIGS. 3 and 4.

In the sloping stringer section c, the web of the shallow channel section 11a is formed with regularly spaced transverse slots 14 for attachments of the steps thereon as will be later described. As will be apparent from FIG. 2, the extremities 15a and 15b of the horizontal end stringer sections a and b, directed towards the columns, are scarfed to interfit with the scarfed outer ends of the cradle members 8a and 8b. The corresponding ends of the shallow channels 11a project substantially above the contour of the V sections so as to engage with the corresponding shallow channels 11 of the cradles and aid in centering the stringer sections with respect to the cradles. The sidewalls of the projecting parts of the shallow channels 11a and 11b are formed with holes 13a and 13b, adapted to register with the holes 13 in the sidewalls of the cradle members.

It will be noted that the scarfed free end of each cradle member has a plate welded across it for supporting the corresponding scarfed end face of the stringer. Desirably, a yielding seal element is interposed between the adjacent end faces of the stringer and cradle to absorb vibrations as well as thermal expansions and contractions.

Projecting laterally from the sides of the horizontal end stringer sections *a* and *b* near their connections with the sloping stringer section *c* are smaller cradle members *16a* and *16b* comprising flanged V-channels and adapted to receive and support joists *17a* and *17b* provided in the form of channel beams generally similar to the cradles *16a* and *16b*. The joists *17a*, *17b* have horizontal plates welded across their flanges to seal their upper surfaces and said plates project beyond the ends of the corresponding channels to take support on the cradle members *16a* and *16b*.

FIG. 2 illustrates a step member *7* about to be swung into position, as indicated by the arrows *f1* and *f2*, in engagement with a slot *14* of the stringer. The step member *7* is a sheet metal element including a substantially trapezoidal front part *18*, providing the rise of the step, extended laterally by two stifferener sidewalls *19* disposed symmetrically on either side of the step. The step member further includes a rectangular tread portion *20*, which is concealed from view in FIG. 2, but is seen e.g. in FIG. 3. Each step member has associated with it a supporting base-block *21*, comprising welded bent metal sheeting in the general form of a box, with a hook-like strip *22* projecting forward and downward from its rear end. The transverse cross sectional contour of the block *21* is complementary to that of channel *11a*.

Referring to FIG. 3, it will be observed that the channels *11* and *11a* of the cradle member *8a* and the stringer end section *a* differ from each other only in that the web of the channel *11a* of the stringer is positioned somewhat higher than the web of the channel *11*, so as to permit the former to overlie the latter, as is visible in the right part of the figure. This figure clearly illustrates the attachment of each of the steps *7* over the stringer. It is seen that the hook *22* at the rear of the base block *21* of each step *7* is engaged in a slot *14* of the stringer web *11a*, and that the under surface of the bottom sheet element of said base block bears upon the upper side of said web. The tread portions *20* of the steps are provided with facing plates *20a* which may be made of any desired material, e.g. wood or plastic. Shown in dotted outline in relation to the topmost step is the position of the step as its hook *22* is inserted through the corresponding uppermost slot *14* of the stringer and just prior to the step being lowered into its final position, as indicated by the arrows *f3*. The manner of attachment of the step to the stringer will be returned to in greater detail later.

The upper horizontal end section *a* of the stringer is seen to support a facing slab forming part of the floor *5*, and including a base block at its under face, engageable into the recess of channel *11a*, so as to fit therein.

As shown in FIG. 4, the shallow channels *11* and *11a* of the cradle and horizontal stringer section are secured in their interfitted position by means of threaded rods *23* inserted through the registering holes *13* and *13a*, and blocked in position by means of nuts *25* threaded on the rod and acting outwardly on washers *24* having slanting outer faces to fit the slope of the side flanges of the channel sections.

The construction of a step member *7* will now be described in greater detail with reference to FIGS. 5 and 6. The step member is formed from a blank of sheet metal which includes a rectangular part *20* and a trapezoidal part *18* the longer parallel side *de* of which is common to the rectangle as a longer side of the latter. This common side *de* constitutes one of the fold lines about which the blank is bent to constitute the finished step. The trapezoidal part *18* which, as earlier indicated and as will be clear from FIG. 1, provides the rise of the step, is defined by the above-mentioned fold line *de* providing its longer parallel side, a parallel fold line *fg* providing the shorter parallel side of the trapezoidal, and two symmetrical oblique fold lines *ef* and *gd*. From these two lines there extend a pair of trapezoidal side flaps *19*, which constitute the sidewalls *19* of the steps previously referred

to. It will be seen that when the blank is bent along the fold lines *de*, *ef*, *gd* in the manner shown in FIG. 6, the rectangular part *20* constitutes the flap upper tread of the step, the trapezoid *18* constitutes the rise, and the flap *19* constitute said sidewall. The edges *en* and *me* are of equal length and are adapted to be welded together in the fully bent condition of the step and the same is done symmetrically on the opposite side of the step. The small lower rectangle *fgkl* is bent to provide a shelf directed forwardly at the bottom of the riser and on which the rear edge of the tread of the immediate lower step is adapted to be rested so as to be held in the angle enclosed by such shelf and the contiguous riser, as will appear from FIG. 3. The arrows *f4* and *f5* in FIG. 6 indicate the directions of the bending operations. A pair of holes *26* may be formed in the rectangular tread portion *20* for convenience in handling and mounting operations. The resulting step member is lightweight yet very rigid and easy to mount in position. It is equally easy and cheap to make in large quantities, and can be surface treated in any desired manner in the factory for permanent protection.

The procedure used for erecting a flight of stairs, as shown in FIG. 1, will be now described in detail.

After the cradle members *8a* and *8b* have first been assembled to the columns *1a* and *1b* so as to face each other at the respective floors, the stringer is presented so that its horizontal end sections *a* and *b* overlie the respective cradles, and is then eased as indicated by the arrows *f6* in FIG. 2 until the projecting ends of its channel sections *11a* drop into the corresponding recesses in the cradles. It will be noted that these operations are much facilitated by the light weight of the stringer coupled to its high rigidity and strength, a result of the cross sectional shape of the stringer including the deep V-channel *9* and the shallow U-channel *11a*, assembled as described to provide a kind of box girder. If desired, plates of yielding plastic material may be interposed between the contacting surfaces to take up thermal expansions and prevent transmission of vibrations.

With the stringer in place, the floor joist *17b* may be mounted in a somewhat similar fashion, by fitting one of its ends into the cradle member *16b* and its opposite end into another cradle member, not shown, projecting from a suitable joist or beam of the structure. Over the joist *17b* thus mounted and other joists or beams mounted at the same level upon the columns, a flooring slab can then be placed, as by fitting base blocks of the floor slabs, similar to the base blocks *21* of the step members, into channel sections such as *11a* of the joists. The positioning of one or more floor slabs in this way greatly facilitates subsequent erecting operations without requiring scaffolding.

The steps of the staircase can now be mounted. For this purpose the base blocks *21* of the lowermost step member *7* is positioned in register with the U-channel *11a* of the intermediate stringer section *c*, and the step member is then swung as indicated by arrow *f7* (FIG. 3) until the end of its hook *22* presents itself in register with the lowermost slot *14* of the stringer. The hook is inserted into the slot with a few strokes of a mallet, as indicated by arrows *f3*, and the step is thus firmly secured across the stringer, so that it can be trodden on to mount the next step, and so on up the flight of stairs. It will be noted from FIG. 3 that the base block *21* of each step member is blocked in its mounted position by the projecting shoulder of the next higher step, engaging the rear end surface of the block. The rear surface of the base block of the topmost step is in turn blocked by a similar projecting shoulder of the base block of the flooring slab. It can also be noted that the hook *22* extending from the rear of a base block, is positioned below the point of application of the pressure exerted by the step member on the stringer, thereby ensuring full stability for the step in use.

Thus, without having to provide any scaffolding, the erectors are able to reach the top of the stringer, step by step, and then position a floor joist 17a in the manner earlier described followed by a floor slab.

Finally the screw rods 23 are inserted through the holes 13 and 13b (FIG. 4) to block the ends of the stringer in place. For this purpose the nuts 25 are first backed inwards towards the center of the rod, and the rod is inserted in slanted position (arrow f8) into the holes 13 and 13a until a washer has abutted the inner side wall of the channel; the rod is then tipped as indicated by arrow f9 to bring its other end opposite to the hole 13 on the opposite side, and is inserted into the hole as shown by arrow f10. The two nuts 25 are then screwed outwards until they press firmly by way of the washers against the side walls of the stringer.

It will be apparent from the foregoing description that a staircase thus erected can easily be dismantled and reused elsewhere if desired. Such operations are facilitated by the light weight of the component parts of the staircase. The parts are thus both economical of material and of labour and time required for mounting operations. Further, the need for scaffolding is eliminated or greatly reduced.

Referring to FIG. 5, it will be noted that the blank of a step member can be cut out of a simple rectangular sheet element (shown dotted) with very little loss of material and is susceptible of cheap large-scale manufacture. The fully shaped and erected steps, as shown in FIG. 1, are extremely advantageous from the standpoints of economy, rigidity, and convenience, while being attractive in aspect. They may be used as erected, or lined with any desired facing material, including wood, marble slab, plastics, etc.

The base block 21 may be attached to steps members of various forms.

Various changes may be made in the illustrated embodiment within the scope of the invention. Thus in the case of a broad staircase, two or more stringers may be used. The steps may then comprise pairs of step members each similar to the member 7 described, mounted side by side. Alternatively, there may be provided step members having a tread part 20 of increased length with two (or more) spaced base blocks 21 attached in it and provided with hooks 22 engageable with slots formed in the related stringers.

The stringers are not necessarily straight, but may be curved, enabling the construction of curved, including, winding, staircases.

The step members may be secured to the stringers through means other than the hook shown. Thus, pins may be inserted through aligned holes formed in the base blocks and the sidewalls of the stringer channel, in a manner generally similar to that in which the stringer ends are secured to the cradle members by way of the aligned holes 13, 13b, with suitable means being provided for retaining the pins in position. The pins may, moreover, be provided with annular grooves and shoulders or the like to provide means for centering the base block relating to a step adjacent the one considered. As a further alternative, the relationship between the hooks and apertures may be reversed: thus the stringer may be provided with a longitudinal row of hooks engageable with slots provided in the base of each step.

The base block, instead of being shaped to fit into the recess of a stringer channel may be conformed as an inverted U for example so as to straddle a complementary contour of the stringer.

The various components of the improved staircase, including the stringers, step members, cradles and base blocks may be made of various materials other than metallic, e.g. wood, concrete, and the like.

What I claim is:

1. A staircase comprising at least one stringer and a

plurality of prefabricated step members engageable from above with said stringer at locations regularly spaced along said stringer and extending transversely with respect to the latter, and stringer including an elongated channel member having downwardly converging sides and a bottom web extending between said sides and having transversely elongated slots in said web at locations spaced apart along the stringer, each of said step members including a base having downwardly converging sides engageable with said sides of the channel member to transversely locate the step member with respect to said stringer when being lowered onto the latter, said base of each step member further having a flat-webbed hook extending from the bottom of said base and opening forwardly below the latter so as to be guided transversely into step-securing engagement with one of said slots by the interengagement of said sides of the base and channel member when a step member is lowered onto the stringer, and means on each step member interlocking with the next lower step member on said stringer to prevent movement of said next lower step member in the direction for disengaging said flat-webbed hook from the slot of said bottom web in which it is engaged.

2. A staircase comprising at least one stringer and a plurality of prefabricated step members engageable from above with said stringer at locations regularly spaced along said stringer and extending transversely with respect to the latter, said stringer including a generally V-shaped elongated outer channel member of sheet metal and a relatively shallow channel member also of sheet metal nesting in the upper portion of said outer channel member and having downwardly converging sides and a bottom web therebetween having transversely extending slots at locations spaced apart along the stringer, each of said step members including a sheet metal blank bent to form a riser at the front of the step member, a tread extending rearwardly from the top of said riser and a forwardly directed shelf at the bottom of the riser enclosing an angle with the latter, each step member further including a sheet metal base having downwardly converging sides engageable with the similarly converging sides of said shallow channel member to transversely locate the step member with respect to the stringer when being lowered onto the latter, said base further having a flat-webbed hook extending from the bottom thereof and opening forwardly below said bottom of the base to engage in one of said slots for securing the step member on the stringer, said tread of each step member being dimensioned to engage, at its rearward edge, in said angle of the next higher step member and thereby be interlocked with the latter so that each step member is held against movement in the direction for withdrawing its hook from the related slot by the interlocking engagement of each step member with the next higher step member secured on said stringer.
